US00D863416S

(12) **United States Design Patent** (10) **Patent No.:** **US D863,416 S**
(45) **Date of Patent:** **** Oct. 15, 2019**

(54) **CONVERTIBLE GLASSES**

(71) Applicant: **Bunny Eyez, LLC**, Bethpage, NY (US)

(72) Inventors: **Jennifer Hutt**, Roslyn Harbor, NY (US); **Andrea Gluck**, Bethpage, NY (US); **Stacy Fritz**, Roslyn Harbor, NY (US)

(73) Assignee: **Bunny Eyez, LLC**, Bethpage, NY (US)

(**) Term: **15 Years**

(21) Appl. No.: **29/636,664**

(22) Filed: **Feb. 9, 2018**

(51) **LOC (12) Cl.** 16-06

(52) **U.S. Cl.**

USPC **D16/326**

(58) **Field of Classification Search**

USPC D16/306, 302, 303, 326

CPC G02C 5/006; G02C 5/08; G02C 3/04

See application file for complete search history.

(57) **CLAIM**

The ornamental design for convertible glasses, as shown and described.

DESCRIPTION

FIG. 1 is a front perspective view of a first embodiment of convertible glasses, according to the present design;

FIG. 2 is a front view thereof;

FIG. 3 is a rear view thereof;

FIGS. 4 and 5 are side views thereof;

FIG. 6 is a top view thereof;

FIG. 7 is a bottom view thereof;

FIG. 8 is a front perspective view of a second embodiment of convertible glasses, according to the present design;

FIG. 9 is a front view thereof;

FIG. 10 is a rear view thereof;

FIGS. 11 and 12 are side views thereof;

FIG. 13 is a top view thereof; and,

FIG. 14 is a bottom view thereof.

The broken lines in FIGS. 1-14 depict portions of the convertible glasses and form no part of the claimed design.

1 Claim, 10 Drawing Sheets
